UNITED STATES PATENT OFFICE.

ORANGE O. OZIAS, OF DAYTON, OHIO, ASSIGNOR TO THE COMPUTING SCALE COMPANY, OF OHIO.

PRICE-SCALE.

SPECIFICATION forming part of Letters Patent No. 655,729, dated August 14, 1900.

Application filed November 16, 1899. Serial No. 737,254. (No model.)

To all whom it may concern:

Be it known that I, ORANGE O. OZIAS, a citizen of the United States of America, residing at Dayton, in the county of Montgomery and State of Ohio, have invented a certain new and useful Improvement in Price-Scales; and I hereby declare that the following is a clear, full, and exact description thereof, reference being had to the accompanying drawings, in which like letters refer to like parts.

This invention relates to improvements in price-scales, the invention being essentially applicable to weighing-scales, and is more especially, though not exclusively, adapted to that class of weighing-scales known as "price-scales," the objects being, first, to secure a more perfect means for exposing the indications upon opposite sides for the inspection of clerk and customer; second, to provide an improved means for supporting the platform, whereby the parts are more readily adjusted and assembled, and, third, to improve the construction of the bearings of scales.

The invention consists in certain novel details of construction and combinations and arrangements of the parts, all as will be hereinafter described, and pointed out more particularly in the claims.

Referring to the drawings, Figure 1 is a perspective view of a scale embodying my invention, the platform or load-receiver being removed therefrom and stood on end at the side thereof. Fig. 2 is a plan view of a corner of the subplatform. Fig. 3 is an elevation view of the opposite corner thereof, part of the same being broken away for clearness. Fig. 4 is an elevation view of the corner of the subplatform shown in Fig. 2. Fig. 5 is an enlarged sectional plan view on line X X of Fig. 3. Fig. 6 is an enlarged end elevation view of the left-hand end of the top part of Fig. 1. Fig. 7 is an enlarged elevation view on line X X of Fig. 1, the extreme upper portion thereof being partly broken away. Figs. 8 and 9 are respectively side and end elevation views of the bearing-block.

In the drawings, 10 illustrates the scale-base, provided with the platform-supporting levers of the general or any desirable construction connected to the steelyard-rod 11, connected at its upper end to the lever 12,

fulcrumed in the housing 13, supported near opposite ends upon the outwardly-curved columns 14, which columns are secured at 55 their lower ends near opposite corners of the base 10.

Within the base 10 is mounted a subplatform-frame 15, having a pair of downwardly-extending legs 16 at each of its corners, said 60 legs 16 at each corner being connected in the instance shown in Figs. 3 and 4 by a cross-piece 17. Near the lower ends and between each pair of legs 16 is a metallic block 18, provided with an opening 19 therethrough near 65 its top. Through each opening 19 is passed a rod 20, whose opposite ends occupy openings in the legs 16, said rod 20 loosely bearing in said opening 19 or said openings in said legs 16. In the lower ends of each of said blocks 18 is cut 70 a slot 21, Fig. 9, into which is placed a portion 22, of agate, steel, or other suitable hard material, preferably agate, provided with tapering sides 23, which converge downwardly, leaving the portion 22 thicker at its top and thinner 75 at its bottom on two sides, so that when the portions 22 are inserted into the slots 21 of their respective blocks 18 and the walls of slots 21 pressed inwardly, said portions 18 being of brass or other suitable soft material—preferably, though not necessarily, of such soft material—said portions 22 will be firmly held from dropping downwardly out of slots 21 of portions 18 by the walls of said slots 21 conforming to the keystone-shaped 80 opposite sides of said portions 22, while greater pressure is applied to the edges of the walls of slots 21 of portions 18, which overlap said keystone-shaped portion 22, so that the metal forming said overlapping edges will be pressed 85 around the corners of the portions 22 to form projections 24, for preventing the said portions 22 from being laterally displaced from said slots 21 at their respective portions 18. Some of said portions 22 are adapted to be 90 provided with a substantially-V-shaped depressed bearing-seat to receive and accommodate the knife-edge of the load-receiving bearings 25 of the platform-supporting levers, while others of said portions 22 are adapted 100 to be provided with the substantially-flat bearing-seat, so as to obviate the necessity for accurately spacing apart several sets of legs 16 or the portions 22, pivotally carried

thereby, thus facilitating the manufacture of the scale and its assembling by unskilled persons, who in use are frequently required to assemble the scale after being shipped or 5 after being cleaned and for other purposes.

The bearing-pin 20, which pivotally supports portions 18 relatively with the legs 16, is at right angles to the pivots 25 of the platform-supporting levers, while in the instance 10 shown in Figs. 3, 4, 8, and 9 the opposite walls of slot 21 in each of said portions 18 are parallel to and on opposite sides of their relative pivots 25, thus leaving between said projections 24, Fig. 5, an opening in each of said 15 portions 18, through which practically all of the opposite ends of the portions 22 are exposed to view.

The ends of the legs 16 project below the lower edges of the walls of slot 21 and of portions 22, and in order to prevent the knife-edge of the load-receiving pivots 25 of the platform-supporting levers from entering the joint between the downwardly and inwardly converging walls of the slot 21, Figs. 3 and 4, 20 a projection 26 extends inwardly from the bottom of each of said legs 16, and the inner ends of said projections 26 project substantially over the edges of the portions 22, so as to prevent said knife-edge of pivots 25 from 25 accidentally getting into the joint between said walls of slot 21 in portion 18 and the opposite sides of portion 22, while in order to deflect said pivots 25 from said portions 26 and into the bearing-seats formed in said 30 portions 22, should said pivots accidentally contact with said portions 26, said portions 26 are formed on their lower sides with an upwardly and inwardly converging surface, and in the instance shown in Figs. 3 and 4, 35 said portions 26 are given said upwardly and inwardly converging angle by being formed of relatively flat strips secured to the upwardly-beveled inwardly-converging bottoms of the legs 16.

40 Upon each corner of the subplatform 15 is a rest projection 30, having projecting therefrom a pin 31, occupying a relatively-small portion of the surface of said projection 30, the tops of said pins 31 being tapered toward 45 a point, as shown in Figs. 3 and 4, and adapted to rest upon the top surface of said projections 30 is a platform or load-receiver 32, Figs. 1 and 4, provided upon its under side with recesses 33, adapted to be occupied by said pins 50 31 when said platform 32 rests upon said projections 30 and said projections 30 raise said platform from above the ordinary unfinished top surface of the subplatform 15. This forming of the pins 31 upon the top surface of the 55 projections 30 further simplifies the machining of the holes 33 in the platform 32, so that a combined drill and counterbore may be used for forming said holes 33 in the platform 32 when said platform is of metal or other substance that can be drilled and by the same operation machine the bottom surface of the 60 platform 32, surrounding said openings 33, so

as to form a finished surface in the proper plane, so that said finished surface surrounding said recesses 33 may firmly and evenly rest 70 upon the top faces of projections 30, while pins 31, entering the recesses 33, prevent said platform 32 from being displaced laterally with relation to the subplatform 15.

In the instance shown in Fig. 1 the right-hand end of the housing 13 is provided in its top with a slot 35, over which is secured an arm 36, Figs. 1 and 7, which arm 36 is connected through said slot 35 to a loop 37, in which is fulcrumed by knife-edged bearings 80 38, Fig. 7, the end of lever 12, near the center of which lever 12 is pivotally connected the upper end of rod 11, which construction is more fully shown in my Letters Patent No. 625,798, for a price-scale, dated May 30, 1899, in Figs. 85 1 and 8 thereof, the top construction thereof being similar to said construction shown in said Letters Patent, except that the poise M of said Letters Patent slides upon a graduated bar in its movement to designate the different 90 rows of price graduations upon the price-indicating chart E of said Letters Patent, (shown more clearly in Fig. 7 of said Letters Patent;) but in my present invention said poise M slides upon a substantially-vertical 95 bar 40 unprovided with indications and secured by angle-irons 41 to opposite ends of the casings F and K or otherwise secured. Adjacent said bar 40 and on opposite sides thereof and arranged at an angle therewith 100 and substantially tangent to the casings F and K are bars 42 and 43, graduated to indicate weight or otherwise, said bar 42 being arranged adjacent and, in the instance shown in Fig. 1, above the slot in casing K, through 105 which the price graduations upon the chart E are adapted to be exposed to view, while secured upon opposite sides of said poise M are indicating-pointers 44 and 45, respectively, each provided with an indicating projection 110 46 upon the edge of said pointers 44 and 45 adjacent the zero-mark upon said graduated bars 42 and 43, while the opposite edges of said pointers 44 and 45 are provided with projections 47, extending beyond said indicating projections 46 to hide from view the indications adjacent the indication designated by said indicating projection 46.

115 From the foregoing construction it will readily be seen that while the price indications upon the chart E are indicated through the slot in casing K by the projection 50, Fig. 1, carried by said poise M, (which projection 50 is adapted to be similar to the projection of poise M, shown in Fig. 7 of the aforementioned Letters Patent,) together with the weight 120 of the load indicated by indicating projection 46 upon bar 42 for the inspection of the merchant or his clerk, so that both the weight and the price of the load are simultaneously 125 indicated, in addition thereto the weight of the load is simultaneously indicated to the customer by the indicating projections 46 upon the graduated arm 43, so that the mer-

chant or his clerk may know the weight of the load and the price to charge therefor, while the customer will simultaneously see the weight of the load. It will be observed 5 that the bars 42 and 43 are adapted to be arranged at such an angle with relation to the bar 40, upon which poise M slides, that said bars 42 and 43 are substantially at right angles to the line of vision, thus enabling the 10 graduations upon said bars 42 and 43 to be readily read, which reading is facilitated by the projection 47, extending below and to one side of the indicating projection 46. A further object of this structure is to prevent the 15 wearing action of the sliding poise M from scraping or wearing the graduated face of the bars 42 and 43.

Having now so fully described my invention that others skilled in the art may make 20 and use the same, what I claim, and desire to secure by Letters Patent, is—

1. In a scale, the combination of a relatively-thin bar mounted in fixed position adjacent an indicating-bar, said indicating-bar being 25 at an angle to said first bar, a poise slidable with its gravity bearing downward upon the thin edge of said bar, the said point of sliding contact between said first bar and said poise being near the top of said poise, and a 30 relatively-light pointer carried by said poise and projecting at an angle over and out of contact with the indicating-surface of said indicating-bar, said first bar being free from indications and forming only a slideway for 35 said poise, substantially as specified.

2. In a scale, the combination of a relatively-thin bar mounted in fixed position adjacent indicating-bars on opposite sides of said first bar, said indicating-bars being at an angle 40 to said first bar, a poise slidable upon said first bar, and pointers carried by and projecting at an angle from opposite sides of said poise and extending over and out of contact with the indicating-surface of said indicating- 45 bars, substantially as specified.

3. In a price-scale, the combination of a price-indicating chart revolvably mounted upon a fulcrumed frame, a relatively-thin bar rigid upon said frame, said bar being thin 50 horizontally at right angles to its length, an indicating-bar rigid upon said frame and at an angle to said first bar, a poise slidable on said first bar, with the gravity of said poise bearing downward upon the thin upper edge 55 of said first bar, said bearing-points between said first bar and said poise being near the top of said poise by which said poise is manually moved, a projection carried by said poise for designating the indications upon said 60 price-indicating chart, a second projection carried by said poise at an angle to said poise and extending over the face of and designating the indications upon said indicating-bar, substantially as specified.

4. In a price-scale, the combination of a price-indicating chart revolvably mounted upon a fulcrumed frame, a bar rigid upon

said frame, indicating-bars rigid upon said frame upon opposite sides of said first bar and at an angle to said first bar, a poise slid- 70 able on said first bar, a projection carried by said poise for designating the indications upon said price-indicating chart, a second and a third projection carried by opposite sides of said poise at an angle to said poise and each 75 extending over the face of and designating the indications upon their respective indicating-bars, substantially as specified.

5. In a price-scale, the combination of a price-indicating chart revolvably mounted 80 upon a fulcrumed frame, a casing inclosing said chart, an exposing-opening in said casing through which the prices upon said chart are adapted to be exposed to view, a bar extending substantially the length of said casing and 85 rigidly mounted thereon in a plane passing through the axis of said casing, an indicating-bar upon each of the opposite sides of said first bar and extending substantially the length of 90 said first bar and secured upon said casing at an angle to said first bar, the indicating-bar upon one side of said first bar being adjacent said exposing-opening in said casing, a poise 95 slidable upon said first bar, a projection carried by said poise for designating the indications upon said price-indicating chart, a sec- 100 ond and a third projection carried by opposite sides of said poise at an angle to said poise and each extending over the face of and de- signating the indications upon their respective indicating-bars, substantially as speci- fied.

6. In a scale, the combination with a beam, the platform-levers connected therewith and the knife-edged bearings in said lever sup- 105 porting the platform, a series of downward projections near the edges of the goods-sup- port, a bearing-block yieldingly mounted near the lower end of each of said downward pro- jections, a plurality of said bearing-blocks 110 having a substantially V-shaped seat passing through their downward face for engaging said knife-edged bearings supporting the platform, walls on opposite sides of and ex- 115 tends below the edges of said bearing-blocks, said walls being parallel to said knife-edged bearings supporting the platform, and projections extending from the adjacent faces of said walls at a point below said bearing-blocks and overlapping the opposite edges of 120 said bearing-blocks to prevent said knife-edged bearings being accidentally seated in the joint between said bearing-blocks and said walls, the slot between said walls in which each of said bearing-blocks is mounted being 125 sufficiently large to permit said bearing-blocks being removed therefrom longitudinally relative to said knife-edged bearings supporting the platform, and means removably mounted in each of said slots for yieldingly mounting 130 each of said bearing-blocks, substantially as specified.

7. In a scale, the combination with a beam, the platform-levers connected therewith and

the knife-edged bearings in said lever supporting the platform, a series of downward projections near the edges of the goods-support, a bearing-block yieldingly mounted 5 near the lower end of each of said downward projections, a plurality of said bearing-blocks having a substantially V-shaped seat passing through their downward face for engaging said knife-edged bearings supporting the 10 platform, walls on opposite sides of and extending below the edges of said bearing-blocks, said walls being parallel to said knife-edged bearings supporting the platform, and projections extending from the adjacent faces 15 of said walls at a point below said bearing-blocks and overlapping the opposite edges of said bearing-blocks said projections converging inwardly and upwardly toward the bearing-seat in the bottom face of said bearing-blocks to prevent said knife-edged bearings 20 being accidentally seated in the joint between said bearing-blocks and said walls and to deflect said knife-edged bearings from said projections into the bearing-seats in said 25 bearing-blocks should said bearings contact with said projections, the slot between said walls in which each of said bearing-blocks is mounted being sufficiently large to permit said bearing-blocks being removed therefrom 30 longitudinally relative to said knife-edged bearings supporting the platform, and means removably mounted in each of said slots for yieldingly mounting each of said bearing-blocks, substantially as specified.

35 8. In a scale, the combination with a beam, the platform-levers connected therewith and the knife-edged bearings in said lever supporting the platform, a subplatform between said platform and said lever and having a series of downward projections, a bearing-block yieldingly mounted near the lower end of each of said downward projections, a plurality of said bearing-blocks having a substantially V-shaped seat passing through their 40 downward face for engaging said knife-edged bearings supporting the platform, walls on opposite sides of and extending below the edges of said bearing-blocks, said walls being parallel to said knife-edged bearings supporting the platform, and projections extending from the adjacent faces of said walls at a point below said bearing-blocks and overlapping the opposite edges of said bearing-blocks said projections converging inwardly and upwardly 45 toward the bearing-seat in the bottom face of said bearing-blocks to prevent said knife-edged bearings being accidentally seated in the joint between said bearing-blocks and said walls and to deflect said knife-edged bearings from said 50 projections into the bearing-seats in said bearing-blocks should said bearings contact with said projections, the slot between said walls in which each of said bearing-blocks is mounted being sufficiently large to permit said bearing-blocks being removed therefrom longitudinally relative to said knife-edged bearings supporting the platform, and means at right angles to said slots for removably mounting each of said bearing-blocks in their said projections, substantially as specified.

55 9. In a scale, the combination with a beam, the platform-levers connected therewith and the knife-edged bearings in said lever supporting the platform, a subplatform between said platform and said lever and having a series of downward projections, a bearing-block yieldingly mounted near the lower end of each of said downward projections, a plurality of said bearing-blocks having a substantially V-shaped seat passing through their 60 downward face for engaging said knife-edged bearings supporting the platform, walls on opposite sides of and extending below the edges of said bearing-blocks, said walls being parallel to said knife-edged bearings supporting the platform, and projections extending from the adjacent faces of said walls at a point below said bearing-blocks and overlapping the opposite edges of said bearing-blocks said projections converging inwardly and upwardly 65 toward the bearing-seat in the bottom face of said bearing-blocks to prevent said knife-edged bearings being accidentally seated in the joint between said bearing-blocks and said walls and to deflect said knife-edged bearings from said projections into the bearing-seats in said bearing-blocks should said bearings contact with said projections, the slot between said walls in which each of said bearing-blocks is mounted being sufficiently large to permit said bearing-blocks being removed therefrom longitudinally relative to said knife-edged bearings

supporting the platform, means for removably mounting each of said bearing-blocks in their said projections, a series of projections extending upwardly from near the edges of said subplatform, a pin rising from each of said projections, and a recess in the bottom of said platform adapted to receive said pin, substantially as specified. 75

9. In a scale, the combination with a beam, the platform-levers connected therewith and the knife-edged bearings in said lever supporting the platform, a subplatform between said platform and said lever and having a series of downward projections, a bearing-block yieldingly mounted near the lower end of each of said downward projections, a plurality of said bearing-blocks having a substantially V-shaped seat passing through their downward face for engaging said knife-edged bearings supporting the platform, walls on opposite sides of and extending below the edges of said bearing-blocks, said walls being parallel to said knife-edged bearings supporting the platform, and projections extending from the adjacent faces of said walls at a point below said bearing-blocks and overlapping the opposite edges of said bearing-blocks said projections converging inwardly and upwardly 85 toward the bearing-seat in the bottom face of said bearing-blocks to prevent said knife-edged bearings being accidentally seated in the joint between said bearing-blocks and said walls and to deflect said knife-edged bearings from said projections into the bearing-seats in said bearing-blocks should said bearings contact with said projections, the slot between said walls in which each of said bearing-blocks is mounted being sufficiently large to permit said bearing-blocks being removed therefrom longitudinally relative to said knife-edged bearings supporting the platform, and means at right angles to said slots for removably mounting each of said bearing-blocks in their said projections, substantially as specified. 95

10. In a scale, the combination of a platform, a subplatform therefor, a series of projections extending upwardly near the edges of said subbase, a pin extending upwardly from the top surface of each of said projections, and a recess in the bottom of said platform for each of said pins, substantially as and for the purpose specified. 115 120

11. As an article of manufacture for scales, a bearing-block having a pivotal bearing in one end thereof, a rectangular slot in one face thereof, said slot being substantially at right angles to said pivotal bearing, and a projection at opposite ends of said slot extending partly across said slot, substantially as specified. 125

12. As a new article of manufacture for scales, a bearing-block, a pivotal bearing for said block, a slot in one face of said block extending through said block at substantially right angles to said pivotal bearing, a projection at opposite ends of said slot extending

partly across said slot, and said slot being narrower at its outer face, substantially as specified.

13. In a scale, the combination of a bearing-block, a support for said block, means for pivotally mounting said block in said support, a slot formed through one face of said block, a bearing portion in said slot, projection from a wall of said slot extending beyond one edge 10 of said bearing portion to secure said portion in said slot, a bearing-seat on one face of said bearing portion, a knife-edged pivot adapted to engage in said bearing-seat, and a second slot extending vertically and being unob- 15 structed from said bearing-seat in said bearing portion beyond said block and its said support; whereby said support, block and said bearing portion may be moved vertically to and from engagement with said knife-edged 20 pivot, substantially as specified.

14. In a scale, the combination of a bearing-block pivotally mounted upon a support, a slot formed through one face of said bearing-block, a bearing portion mounted in said slot, 25 projections from said slot extending beyond a plurality of the edges of said bearing portion and partly across said slot for confining said bearing portion in said slot, a bearing-seat formed on one face of said bearing portion, a knife-edged pivot adapted to engage 30

said bearing-seat, and a second slot extending vertically and being unobstructed from said bearing-seat in said bearing portion beyond said block and its said support; whereby said support, block and said bearing portion may 35 be moved vertically to and from engagement with said knife-edged pivot, substantially as specified.

15. In a scale the combination of a member, a block pivotally supported therein, a 40 slot in one of the exterior faces of said block at an angle to the axis of said pivotal support for said block, said slot being tapering on opposite sides toward said exterior face of said block where said slot is the narrowest, a bearing portion in said slot, the opposite sides of said bearing portion being tapering and conforming with the taper of said slot, a bearing-seat upon the outer face of said bearing portion, a knife-edged pivot engaging with said 45 bearing-seat, and means for preventing the movement of said bearing portion parallel to said tapering sides, substantially as specified.

In witness whereof I have hereunto set my hand this 4th day of November, 1899.

ORANGE O. OZIAS.
